MOP

Joseph D. Bates, Springfield, Mass.

Application September 1, 1933, Serial No. 687,902

9 Claims. (Cl. 15—119)

This invention relates to mops and, more particularly, to a roller mop having wringer means carried thereby.

It is proposed by the present invention to provide a roller mop which may be rolled freely in one direction to spread water or other cleaning fluid upon a surface to be cleaned, and which will be held from rotation when moved in the opposite direction in order to wipe the surface over which the cleaning fluid has been spread. In carrying out the invention, I provide a mop roller having a cylindrical layer of mopping material thereon, and associated with which is a one-way braking or locking device which insures that the mop roller will rotate in only one direction.

The invention also includes the provision of means for wringing or squeezing the mopping material which is carried by the mop roller. According to the invention such means comprise a wringer roller which is so mounted with respect to the mop roller that it may be moved about the entire circumference of the mop roller in wringing or squeezing engagement with the mopping material thereon. Means are also provided by the invention for locking the wringer roller in squeezing engagement with the mopping material on the mop roller.

By means of the present invention it will be seen that the mopping material on the mop roller may be squeezed dry of any cleaning fluid therein by locking the wringer roller in squeezing engagement with the mopping material and then moving successive portions of such material into engagement with the wringer roller. In this operation the one-way brake operates to permit rotation of the mop roller to bring successive portions of the mopping material into engagement with the wringer roller, and subsequently permitting free return of the mop roller frame to such a position as to permit another portion of the mopping material to be moved under the wringer roller.

In addition to the objects and general features of operation and construction set forth, it is an object of the invention to provide a mop device which will be light in weight and strong in construction, but which will be of such simple construction that it may be easily and cheaply manufactured and quickly assembled.

Other objects and features of novelty will be apparent from the following description and the drawings, it being expressly understood, however, that the invention is in no way limited by such description and drawings or otherwise than by the appended claims.

Referring to the drawings in which similar reference numerals refer to like parts:

Fig. 1 is a perspective view of the mop device forming the subject of the invention;

Fig. 2 is an end view of the mop device showing the wringer roller in inoperative position;

Fig. 3 is an end view of the mop device showing the wringer roller about to be moved to wringing position;

Fig. 4 is an end view of the mop device showing the wringer roller and frame in wringing position;

Fig. 5 is an end view of the mop device showing the wringer roller and frame about to be moved to inoperative position; and

Fig. 6 is an exploded view showing parts of the mop device.

Referring particularly to Fig. 1 of the drawings, it will be seen that a hollow cylindrical mopping element 1 is provided, the same being formed of any suitable material, although sponge rubber is believed to be preferable. The mop member 1 is sleeved about, and carried by, a cylindrical roller member 2 which is rotatably mounted in the ends of the arms 3, 4 of a U-shaped frame 5 by means of the pins 6, although any suitable supporting means other than such pins may be employed. Attached in any suitable manner to the central portion of the U-shaped frame 5 is a socket member 7 having a generally cylindrical form and into which the end of an operating handle 8 may be received. The socket member 7 is longitudinally split as at 9 in Fig. 1 and ears 10, integrally formed with cylinder 7, are disposed at each side of the split. Aligned screw-threaded holes are formed in the ears and a screw 11 is threaded into the same for drawing the ears together to tighten the socket 7 on the end of handle 8, although it will be obvious that any other suitable means may be employed for this purpose. Formed integrally with each of the ears 10 on the lower sides thereof are depending lugs 12 which provide latching means for a purpose to be explained fully hereinafter.

Means are provided by the present invention for permitting free rotation of the roller 2 and mop 1 when the mop device is moved in one direction, and for causing these elements to be held from rotation when the mop device is moved in the opposite direction, whereby a scraping or wiping action is provided. Such means comprise a circular plate or disc 13, which may be attached to one end of the roller 2 by means such as the screws 14, and which is provided with an annular, outwardly-extending flange 15. Disposed

within the open-sided drum formed by the plate 13 and flange 15 is a one-way braking device or stop member 16 which is eccentrically pivoted to the arm 4 of frame 5 by a pin 17, all as clearly disclosed in Fig. 6. It will be noted that the pin 17 is disposed rearwardly of the radial center line of the brake device 16. The stop member 16 is formed with an inner wall 18 which is closely adjacent the bearing pin 6 but does not touch the same, while the outer wall 19 of the stop member is formed on an arc closely paralleling the inner face of flange 15 and is disposed in very close proximity thereto. The forward portion of the circumferential face of outer wall 19 is provided with a series of teeth 20, the same being inclined forwardly, or in the direction of the arrow A of Fig. 2, while the greater remaining length of this face is smooth, as at 21. A bore or socket 22 is provided in the braking member 16 and extends from the face 18 in a radial direction through the approximate radial center line of the clutch member, terminating intermediate the faces 18 and 19. A coiled compression spring 23 is disposed within the bore 22 and bears at one end against the bottom of the bore and at its other end against the pin or shaft 6. It will be apparent that spring 23 constantly urges the braking member 16 in a counterclockwise direction about the pin 17, thereby urging the teeth 20 into engagement with the flange 15. It will be understood that the spring 23 is very light and exerts only a slight force on the cam or clutch member 16.

Means are provided by the invention for wringing the water out of the mop member 1 when it is desired to do so. Such means comprise a secondary or auxiliary frame 24, the same being U-shaped in construction and comprising the parallel leg members 25, 26 and the connecting piece 27. The ends of the parallel leg members 25, 26 are rotatably journaled on the pins or shaft 6, preferably externally of the legs 3, 4 of the handle-supporting frame. The connecting member 27 of frame 24 is formed of resilient material whereby the central portion thereof may be sprung downwardly to allow the same to pass the lugs 12 on ears 10. By this means it will be apparent that frame 24 may be latched in inoperative position behind lug 12, and may be released from such position by merely springing the connecting member 27 from behind such lug. Referring to the drawings, it will be seen that leg 25 is provided with an integrally-formed offset portion 27 which extends from leg 25 in such a way that the extremity thereof overlies the leg 4 when leg 25 is in inoperative or latched position. Formed in the leg 25 and in the offset portion 27 is a slot 28, the longitudinal length of which is at an angle to the leg 25 and extends from the approximate center line of the leg 25 toward the leg 4. The slot 28 terminates at one end in the offset portion 27 and said end overlies the edge of mop element 1 when the frame 24 is in latched position. This end of the slot 28 is provided with an upwardly-extending recess 31, as disclosed clearly in the drawings. An exactly similar construction is provided on leg 26 of frame 24 and will not be described further in detail.

Disposed between the legs 25, 26 is a wringer roller 32, the same being provided at its ends with pins 33 which ride in the above-described slots in the leg members 25, 26. The length of wringer roller 32 is such that it snugly but freely

fits between the legs 25, 26 and when in such position the end portions of the periphery of the wringer roller abut the edges of legs 4, 5. The diameter of the roller is such, and the length and disposition of the slots 28 are so arranged, that when the frame 24 is in its latched or inoperative position, as in Figs. 1 and 2, the legs 4, 5 will abut the extremities of roller 32 and force the pins 33 to the rearward ends of slots 28 and thereby rigidly maintain the roller 32 in such a position that the periphery thereof will be just barely out of contact with the mop element 1, thus providing a rigid inoperative position for the wringer roller when the same is not in use.

In the operation of the above-described structure, if it is desired to mop or clean any type of surface, the wringer frame 24 is first placed in its inoperative position by engaging the cross member 27 behind the lugs 12 on ears 10, thereby disposing the wringer roller 32 out of contact with the mop element 1, with the pins 33, 34 held in the end of slots 28 by the pressure of legs 3, 4 on the peripheral ends of roller 32, all as clearly shown in Figs. 1 and 2 of the drawings. The mop may now be manipulated over the surface to be cleaned by means of the handle 8. It will be observed that when the mop is moved in a forward direction, as in the direction of arrow A of Fig. 2, the clockwise rotation of roller 2 and flange 15 will exert such a force on the outer peripheral face of the clutch member 16 as to cause the same to move a very slight distance in a clockwise direction about pin 17, thereby slightly compressing spring 23 and moving the teeth 20 on braking member 16 out of engagement with the flange 15. The teeth 20 having been moved out of engagement with flange 15 it will be apparent that the roller 2 and mop element 1 will be free to rotate in a clockwise direction, as viewed in Fig. 2, as long as the mop is moved forwardly, as shown by the arrow A in Fig. 2. In this way, water with which the mop element 1 has been saturated, may be spread freely on the surface to be cleaned.

If it is now desired to cause a wiping or scrubbing effect on the surface to be cleaned the mop may be moved rearwardly over such surface, i. e., in a direction opposite to that of the arrow A of Fig. 2. When such rearward movement is initiated, it will be apparent that the clockwise force exerted by flange 15 on the outer peripheral edge of braking member 16 will be relieved and the spring 18 will therefore move the member 16 in a counterclockwise direction about the pin 17, whereby the teeth 20 on member 16 will be moved into engagement with the inner periphery of flange 15. As soon as such engagement occurs, any further force tending to move flange 15 in a counterclockwise direction will cause the teeth 20 to tightly grip the flange and, due to the eccentric mounting of the member 16 on pin 17, these teeth will be tightly forced into engagement with the flange, whereby further counterclockwise rotation of the flange 15, roller 2 and mop element 1 will be prevented and the mop element will be wiped or scraped across the surface to be cleaned as the entire mop structure is moved in a rearward direction.

If it is now desired to wring the water or other cleaning fluid out of the mop element 1, such operation is performed by manipulation of the wringer roller 32. Such roller is normally positioned as shown in Fig. 2, being held out of engagement with mop element 1 as described hereinbefore, and the wringer frame 24 being held in

75

inoperative position by lug 12. In order to operate the wringer, the frame 24 is first detached from behind lug 12 by depressing the central portion of cross member 27. The entire wringer frame with the wringer roller carried thereby is now moved in a counterclockwise direction about the pins or shaft 6 until the ends of the periphery of the wringer roller abut the edges of legs 3, 4, such position being clearly disclosed in Fig. 10 3 of the drawings. Further counterclockwise movement of frame 24 forces the wringer roller 32 against the legs 3, 4 whereby the pins 33 on such roller will be moved in the slots 28 toward the recess 31 and against the tension of the mop element 1 exerted on the roller. Sufficient force 15 may be exerted on the frame 24 as described above to cause the pins 33 to be moved to the lower extremities of slots 28 and, by reason of the radial tension exerted by the mop element 1 on the wringer roller, such pins will be forced 20 into the recesses 31 at the extremities of the slots and maintained therein by the tension of the mop element exerted on the face of the wringer roller. The parts are so designed, as described hereinbefore, that when the pins 33 are disposed 25 within the recesses 31 the mop element, or a portion thereof, will be compressed between the wringer roller and the roller 2 within the mop element. The parts are now in the position disclosed in Fig. 4 and, if the wringer roller frame 30 is now moved in a clockwise direction while the mop frame is held from movement, the mop roller 2 and mop element 1 will also be moved in a clockwise direction about the pins 6. Such 35 movement of the mop roller and mop element is caused by the engagement between the mop roller and wringer roller due to the fact that the mop element 1 is tightly compressed between these two rollers, thereby acting in the manner 40 of a connection between the two rollers. When such clockwise movement is initiated, the clutch member 16 is moved slightly in a clockwise direction about the pin 17, whereby the teeth 20 on the braking member 16 are removed from engagement with flange 15 sufficiently to permit 45 free rotation of the flange, mop roller and mop element in a clockwise direction with the wringer frame and wringer roller.

If the wringer frame and wringer roller are 50 now moved in the reverse or counterclockwise direction about the pins 6, it will be apparent that the teeth 20 on member 16 will engage the inner periphery of flange 15 in the manner described hereinbefore, thereby preventing counterclockwise rotation of the flange 15, mop roller 2 and mop element 1. The wringer frame and wringer roller carried thereby are, of course, free 55 to rotate in either direction, and a relative movement is therefore caused between the mop roller 60 and element and the wringer frame and roller, the mop roller and element remaining stationary while the wringer frame and roller move in a counterclockwise direction. It will be apparent that as the wringer roller is moved in a 65 counterclockwise direction over the stationary mop roller and mop element, successive portions of the mop element will be compressed between the mop roller and the wringer roller, thereby squeezing the water out of the mop element. 70 It will also be apparent that a reciprocating movement of the wringer frame will successively compress a certain portion of the mop element and then rotate the mop element and mop roller whereby a new portion of the mop element may 75 be compressed, and that this operation may be

continued until the entire mop element has been freed from water.

When the wringing operation is completed the wringer frame may be moved to the position shown in Fig. 5, wherein the arms 3, 4 of the mop frame abut the ends of the periphery of the wringer roller. Further movement of the wringer frame will cause the arms 3, 4 to force the pins 33 out of recesses 31 and into the other ends of slots 28 to the position shown in Fig. 2, 10 the wringer frame being maintained in such position by engagement of the cross member 27 behind the lug 12.

While I have described and illustrated certain embodiments of my invention, it is to be understood that further modifications and improvements are contemplated and may be practiced without departing in any way from the spirit of the invention, for the limits of which reference must be had to the appended claims.

What is claimed is:

1. A mop comprising a U-shaped frame, a mop roller journaled in the open end of said frame and having an outer surface of mop material, a second U-shaped frame journaled at its open end to said mop roller for movement around the periphery thereof, said second frame having aligned slots in the side members thereof and extending toward said mop roller, and a wringer roller journaled in said slots and movable therein from a position removed from said mop roller to a position in engagement with said mop roller for wringing said mop roller.

2. A mop comprising a frame, a mop roller journaled in said frame, a second frame pivotally mounted with respect to said mop roller and movable about the periphery thereof, said second frame having slots therein extending toward said mop roller, a wringer roller journaled in said slots and movable therein into engagement with said mop roller, and means operable when said wringer roller is engaged with said mop roller and said second frame is rotated about said mop roller for preventing rotation of said mop roller in one direction and permitting rotation thereof in another direction.

3. A mop comprising a frame, a mop roller journaled in said frame and having a surface of resilient material, a second frame journaled to said mop roller and having therein aligned slots extending toward said mop roller and communicating laterally extending locking recesses at the ends of said slots which are toward the mop roller, a wringer roller journaled in said slots and movable toward said mop roller and adapted to be locked in wringing position in said recesses by said mop roller, whereby the mop may be wrung upon relative rotation between the second frame and the mop roller.

4. A mop comprising a frame, a mop roller journaled in said frame and having a surface of resilient material, a second frame pivotally mounted with respect to said mop roller and movable about the periphery thereof and having therein aligned slots extending toward said mop roller, and communicating laterally extending locking recesses at the ends of said slots which are toward the mop roller, a wringer roller journaled in said slots and movable toward said mop roller and adapted to be locked in wringing position in said recesses by the material on said mop roller, and means for holding said mop roller from rotation in one direction whereby relative wringing movement of said wringer roller and mop roller may be effected.

5. A mop comprising a frame, a mop roller journaled in said frame, a second frame journaled to said mop roller for movement around the periphery thereof and having aligned slots 5 therein extending toward said mop roller, a wringer roller journaled in said slots and movable therein toward and away from said mop roller, and means for locking said wringer roller in said slots in engagement with said mop roller.
- 10 6. A mop comprising a frame, a mop roller journaled in said frame and having resilient mop material on the surface thereof, a second frame journaled to said mop roller and having side arms in which are formed aligned slots extending to 15 ward said mop roller and having recesses communicating with said slots at the ends of said slots adjacent said mop roller and extending laterally of said slots, a wringer roller journaled in said slots and movable therein toward and away 20 from said mop roller, the peripheral portions of the ends of said wringer roller overlapping and abutting portions of said first-named frame, said resilient mop material and said wringer roller cooperating to maintain said wringer roller in 25 said recesses when said wringer roller is in wringing position.
7. A mop comprising a U-shaped frame, a mop roller journaled in the open end of said frame and having an outer face of mop material, a second U-shaped frame journaled at its open 30 end to said mop roller for movement about the face thereof, a wringer roller so carried by said second frame as to be movable in said frame from a position removed from said mop material

to a position in wringing relation to said mop material, and means for preventing rotation of said mop roller in one direction when said wringer roller is engaged with said mop material and is rotated about the periphery thereof.

5

8. A mop comprising a frame, a mop roller journaled in said frame and having an outer face of mop material, a second frame journaled to said mop roller for rotation about the periphery thereof, a wringer roller so mounted in said second frame as to be movable therein from a position removed from said mop material to a wringing position in engagement with said mop material, means for locking said wringer roller in wringing position, and means for holding said 15 mop roller from rotation in one direction when said second frame and wringer roller are moved about the periphery of said mop roller.

9. A mop comprising a U-shaped frame, a mop roller journaled in the open end of said frame and having a cylindrical layer of mop material on the surface thereof, a second U-shaped frame member having said arms journaled to the ends of said mop roller, said side arms being provided with aligned slots extending to 25 ward said mop roller and having aligned recesses at the ends thereof toward said mop roller and which extend laterally of said slots, a wringer roller journaled in said slots and movable therein toward and away from said mop roller, said 30 mop material and said wringer roller cooperating to maintain said wringer roller in said recesses when said wringer roller is in wringing position.

JOSEPH D. BATES.
